UNITED STATES PATENT OFFICE.

CYRENUS WHEELER, JR., OF AUBURN, NEW YORK.

IMPROVEMENT IN HARVESTERS.

Specification forming part of Letters Patent No. 632, dated March 12, 1861; reissue No. 4,946, dated June 11, 1872.

DIVISION B.

To all whom it may concern:

Be it known that I, CYRENUS WHEELER, Jr., of Auburn, county of Cayuga, State of New York, did invent certain new and useful Improvements in Reaping and Mowing Machines, of which the following is a full, clear, and exact description, reference being had to the accompanying drawing making a part of this specification, in which—

Figure 1 represents a perspective view of the machine when arranged for mowing grass. Figs. 2, 3, 4, 5, 6, 7, 8, 9, 10 represent details of the machine which will be hereinafter referred to. Fig. 11 represents in perspective the machine (when arranged for mowing grass) as having its finger-bar folded up for transportation from place to place. Fig. 12 represents in perspective the machine as arranged for reaping grain.

Similar letters of reference denote corresponding parts in all the figures.

This invention relates to a combined reaping and mowing machine, convertible to either purpose, and embracing the necessary elements to adapt it to either use. The invention embraced in this division of the application relates to the manner of combining in a rear-cut vibrating-frame machine a laterally-projecting cutting apparatus, which has two hinges or centers of vibration, adapting it to follow the surface of the ground independently of the driving or main carrying wheels, a side delivery-platform and reel supported wholly on the hinged cutting apparatus and platform so as to conform fully to their movements; to the arrangement of the hinges of the cutting apparatus, and platform and lever for tilting the same, and to the manner of mounting the platform caster-wheel, whereby it is prevented from becoming clogged or obstructed, as is hereinafter set forth.

To enable others skilled in the art to make and use my invention, I will proceed to describe the same with reference to the drawing, and, first, as adapted to mowing grass.

A rectangular frame, A, is suspended to the axle B by suitable boxes C so that it may swing on said axle. On this axle B, and outside of the frame A, are the two main carrying and supporting wheels D D', the latter, D', being also a driving-wheel, and for this purpose revolv-

ing with the axle, while its mate or fellow D is loose upon and may turn independent of the axle. On the front part of the main frame A there is a shaft, a, supported in boxes b. One end of this shaft has upon it a pinion, c, that gears with the cogs d of the drive-wheel D', and thus a rotating motion is communicated to this shaft a, and through it to the cutters, as follows: A bevel-wheel, E, on the shaft a, meshes with a bevel-pinion, e, on a shaft, f, that extends rearward and inclines downward and rotates said shaft f. The shaft f has a crank-wheel, g, on its extreme rear end, and to a wrist-pin in this crank-wheel the pitman h is attached by one of its ends, the other end thereof being connected to the cutter-bar i, and through this gearing the cutter-bar is vibrated. In order that the cutter-bar may be at rest when the machine is not cutting grass or grain, I have arranged a clutching and unclutching apparatus for engaging or disengaging the bevel-wheel E and the bevel-pinion e, as follows: A plate, j, is bolted to the main frame, in the top of which there is an oblique slot, k, that has a recess at both ends of it, so as receive and hold a lever, l, that works through said slot when said lever comes opposite either of said recesses, it being thrown and held in them by a spring, m, upon its side, that presses it in that direction. Underneath the slot there is a way, n, that inclines in the same direction with said slot, and upon this way n a carriage-plate, o, is moved, that has a flange, p, upon it, that projects into a groove formed in the axle or shaft a, so that sliding the plate o obliquely moves the shaft endwise, drawing it away from or forcing it up to the pinion c, as the case may be, and in either case the lever is held at the end of its motion by one or the other of the recesses in the oblique slot k, into which it is thrown by its spring m. To move the lever, it is first forced against its spring m until it leaves the recess, then moved in the direction of the slot.

At the rear end of the main frame, and on the grain side thereof, there is bolted a quadrant or sector-plate, F, and to this plate, or through it and to the main frame, is pivoted, by a pivot-bolt, q, a movable quadrant or sector-plate, G, that is in contact or close proximity to the stationary one F. That the plate

G may work freely on its pivot without being shackling, it moves through a guide-piece, r, at its front, and has a restraining piece, s, toward its rear, which steadies it to the rigid plate F. A hand-lever, t, is connected to the moving sector-plate G, and to this is pivoted a latch or locking-lever, u, with a spring, v, behind it. The lower end of the latch-lever is bent into a hook-form, and, passing through an opening in lever t and plate G, will catch, if unrestrained, into one of the series of holes 1, 2, &c., in the stationary plate F, and thus lock the two plates together. By slipping a ring over the lever t and over the latch-lever u so as to hold them close together, this locking cannot take place, and then the plate G can move on its pivot until its shoulder w comes against a pin set in the hole 3, where it is stopped, that pin being at a point where it will catch the finger-bar before the points of the fingers would be apt to run into the ground by their downward inclination. The plate G has other devices connected with it, viz., the projections x x, to which the shoe H is pivoted, and a hinged hook and latch, y, which holds the lever I in two positions, as will be described hereafter.

The shoe H is pivoted to the arms or projections x x at z z, through lugs 1 2 at its front and rear, and the finger-bar J is connected to the shoe by means of a recess and bolts or rivets, to give it the proper degree of strength. To the outer end of the finger-bar is attached the outside divider K. This divider has a recess, 3, (see Figs. 1, 7 and 8,) in it, in which is secured a plate, 4, having horizontal lugs 5 on it, through which an inclined pivot-pin, 6, passes to form a hinge for the curved shank L, to which the outside caster-wheel M is hung. When the machine is drawn forward, the caster-wheel and its curved shank swing backward and behind the path of the divider K, as seen at Figs. 1 and 7, which allows the finger-bar and its several appliances to come down close to the ground; but when the machine is being geed around, or turned to the right hand, the caster and its shank swing into the position shown in Fig. 8, which raises up the shoe or divider and outer end of the finger-bar, as shown by the comparative height of the divider above the horizontal line under the casters, in Figs. 7 and 8. I use but one shank for my caster-wheels, said wheels being hung to the side of the shank. This prevents the accumulation of straw and other obstructing material, and avoids the choking and clogging of the wheel incident to its use when working between two legs or shanks.

To the rear end 7 of the outside divider K is bolted or pivoted the track-clearer N, which is made as follows: A metallic shoe-piece, 8, is secured at its point to the divider K. This shoe-piece has flanges or lugs 9 turned upon it, through which a vertical pivot passes to form a hinged connection between said shoe and the vertical (or nearly so) board 10. The track of the shoe-piece 8 extends rearward and

forms a shank, 11, which lies snugly up against the board 10. On the outside of the board 10 there is a pivot-catch, 12, (see Fig. 4,) which, when let down upon its stop 13, overlaps the shank-piece 11 and thus makes the shoe and board rigid and as though made of one piece; but by raising up the rear end of the catch-piece 12 to a vertical (or nearly so) position, it releases the catch-piece, and the board will swing freely in one direction (viz., away from the standing grass) on its hinged connection. The track-clearer may thus be a rigid or a hinged one, as may be preferred, or as its special duty may require. 14 is the handle by which the track-clearer may be handled or moved. The object of the track-clearer is too well known to need any further description of it.

Or are the fingers or guards on the finger-beam J, and 15 are the guides thereon for the cutter-bar i to work through. The construction of the guards and the action of the cutter therein will be more clearly understood by reference to Fig. 10, where an enlarged sectional view of a guard and its several parts is seen. The guard is cast in two pieces—an upper one, 16, and a lower one, 17—each having projections and recesses, as seen in said Fig. 10. In a recess in the lower part 17 is placed what I term a ledger or cutter plate, 18, resting upon its lugs 19 in said recess. The upper portion 16, after the lower portion 17 is bolted to the finger-bar, as at 20, and the cutter-plate laid in, has its point 21 slipped under the cap 22, and then brought down until its rear 23 comes upon the rear portion 24 of the underpart, where the two parts are bolted together, as at 25. The projection 26 rests upon the heel of the cutter-plate, keeping it firmly in place, and the other one 27 rests behind the finger-bar, so that the two bolts 20 and 25 hold the fingers to the bar and its parts to each other, and also the cutter-plate in its proper position, leaving room for the cutter-bar and knives to freely play through. The object of the cutter-plate is to make a shear-edge, as it were, for the cutters to cut against. This construction and connection of guards afford easy access, removal, replacement, or repair of any of its parts or appliances. P is a second frame hinged to the axle at 28, and extending rearward and over the rear portion of the main frame. At the rear of this second frame is pivoted, by a vertical pivot, 29, the shank Q, which has connected to it the caster-wheel R, the caster-wheel, like the one M above described, being hung to the side of the shank. This caster-wheel may be also so hung as to slightly raise up its frame when the machine is being turned around, and let it down again when the machine starts forward. And as the main frame is sometimes suspended to this second frame, this raising and lowering may be important. To the second frame P is pivoted at 30 the seat-support S, which carries the seat T, and, by a series of holes and a pin, 31, the position of the seat

may be varied to allow the driver to face the team or the cutters, whichever requires his attention the most. A plate, 32, is bolted to P, which has a journal, 33, projecting from it, and a ratchet-arc, 34, fastened to it. On the journal 33 is placed, so as to turn freely thereon when required, a pulley, 35, which has a hand-lever, 36, fastened to it, and to this lever, 36, is pivoted a latch-lever, 37, which has its lower end turned so as to stand at right angles and pass through an opening in lever 36 and to take into the notches in ratcheted arc 34, the spring 38 serving to throw it in that direction. A chain, 39, which is fastened to the main frame, is hooked to the pulley 35, so that the operator, by seizing the hand-lever 36 and pressing the top of the latchet-lever 37 toward the hand-lever 36, withdraws the locking-end and he can raise or lower the main frame, at pleasure. When the main frame is suspended to the second frame P they can only move together upward by anything coming under the rear caster R; but the flexibility of the chain 39 will allow the main frame to rise independently of the rising of the second frame, though suspended to it; and when the main frame is let down and the chain slackened either frame may move on the axle independent of the other. The lever I, Fig. 3, is mounted on the same pivot which hinges the shoe to the pivoted quadrant or sector plate, and has a foot, 40, on it, which bears upon the top of the shoe H. By seizing this lever and drawing it toward the main frame the driver or operator may raise up the outer end of the finger-bar, and the latch 41, catching over a pin in the lever, will hold it thus raised up. The hook y keeps the lever up within reaching distance of the operator from his seat. The latch-lever u and hand-lever t are for raising or lowering the points of the fingers and cutters, and holding them at any desired angle for cutting a higher or lower stubble in mowing; or adjusting the same, and the platform and reel and gathering mechanism thereon, in reaping.

When the finger-bar is to be folded up into the position shown in Fig. 11 for transportation, it may be first raised up into a perpendicular position. The pin is drawn from the hole 3, the locking-lever u is pulled back to hand-lever t, and the plate G, to which the finger-bar is pivoted, is free to turn forward, and the finger-bar with it, until the point of the outside divider K rests in a supporting-arm, 42, on the front of the frame A, where it will ride well balanced, the arm 42 preventing it from swinging in or out.

The tongue U is hinged to the front of the main frame at one side thereof to counteract side draft and opposite to it, at the other corner, is a shoe, V, for receiving the post that sustains the driver's seat (as shown in dotted lines) when the machine is converted into a reaper, as will be hereafter explained.

Fig. 2 represents a reel-post which is used when the machine is arranged for reaping grain,

and Fig. 6 represents a caster which belongs to the grain-table; both of these will be more particularly mentioned in describing the arrangement for reaping, and to which they properly belong.

To convert this machine from a mower to a reaper the track-clearer N, the outside caster M, and the lever I are removed. The grain-table W is adjusted and bolted to the finger-beam. The reel-post X, Figs. 2 and 12, is fitted on where the lever I comes off. The belt-guide Y is set in the socket prepared for it. The driver's seat Z is set in the shoe V. The platform or grain-table has upon it the outside reel-post A' and its caster B', and a long divider, C', that lies up against the shoe K, but projects beyond it; and when the reel D'' is set in its supports and the band E' adjusted over its pulleys F' G', and through the guide Y, and the finger-bar set up or raised to the proper height, the machine is ready for reaping grain.

The necessity of the belt-guide is this—that the outer end of the finger-bar and the platform is still free to rise and fall to the slopes of the ground, and, if not controlled, the reel-shaft moving with the platform would throw off the belt; but the guide Y prevents it, as any end motion of the reel-shaft is not transmitted to the belt beyond said guide.

It is unnecessary to further describe in detail the construction of the parts which convert the machine from a grass to a grain cutting machine. It has all the necessary elements within itself for either work. The finger-bar can be raised or lowered at either end or at both ends; it can be turned to raise or lower the points of the guards; it can conform to the ground at one end or at both ends; it is self-yielding or flexible; it can be folded up out of the way, and work with or without the grain-table.

The seat T, mounted on the frame P, serves the double purpose of a driver's seat when mowing grass, and a raker's seat when reaping grain. The raker, sitting on the seat T, which is adjustable, can face the team, or sit obliquely to the falling grain and deliver the same in gavels, at the side of the platform, out of the way of the team in the next round.

On the foot of the reel-post X there is a projection, 43, by which it is secured to the lug I on the shoe H, and also an arc, 44, furnished with holes for lowering or raising, and holding the reel-post when adjusted. When the machine is arranged for cutting grass, or the reel removed, the reel-post is also taken off; and when the reel-post is on the lever I is removed.

Having now described my invention, what I claim in this division is—

1. A cutting apparatus and platform, connected with the frame of the machine by two hinges whose axes of motion are at right angles to each other, substantially as described, in combination with an apparatus for reeling in the grain, mounted wholly on said platform

and cutting apparatus in such manner as to conform to their movements on both hinges.

2. A cutting apparatus and platform connected to the frame by two hinges at right angles to each other, as above described, and carrying the reeling apparatus, in combination with a lever arranged within reach of the attendant, who from his seat can rock or roll the cutting apparatus and platform, together with the reeling apparatus supported thereon.

3. In combination with the laterally-projecting hinged cutting apparatus and the grain-platform attached thereto, a caster platform-wheel, which is hinged to the platform by an

inclined pivot and has its axis supported on one side only.

4. In combination with a hinged finger-bar and platform that are free to rise and fall at their outer ends and that carry the reel-supports, a belt-guide on the main frame to prevent the end motion of the reel-shaft from throwing the belt off from its driving-pulleys, substantially as described.

C. WHEELER, JR.
